UNITED STATES PATENT OFFICE

WILLIAM ALDERSON, OF SACRAMENTO, CALIFORNIA

VERTICALLY-FOLDING DOOR

Application filed December 27, 1928. Serial No. 323,810.

This invention relates to door construction and particularly to doors for use in garages, warehouses and similar buildings which require relatively large doors.

The principal object of my invention is to provide a door construction for this purpose arranged so as to open vertically and in such a manner that the opening movement will take place automatically as soon as the holding latch is released, while at the same time permitting of easy manual closing of the door.

A further object of the invention is to construct the door so that said door and its frame are arranged as a unit which may be readily installed in connection with the surrounding framework of a building without any structural changes in the latter being necessary over present methods. The door structure occupies but little space when raised and is arranged so that it may be then enclosed in a transverse space no wider than an ordinary wall so as not to project on either side of the wall, while at the same time it requires very little greater height to then receive it than is afforded by the ordinary door casing.

The door, as above stated, is arranged to open automatically when released and I have therefore provided a catch release means adapted to be actuated some distance from the door and to one side of the same so that said door may be caused to open by the driver of a car approaching the garage without his having to leave the vehicle.

While the door and its frame are of metal so as to be of a fireproof nature and therefore useful in any place where a fireproof door is required, the parts are so arranged that the structure as a whole can be made very cheaply (in fact as cheap as a wooden door structure); while said parts being assembled in the factory as a unit with the frame the structure is very easy to install in place.

These objects I accomplish by means of such structure and relative arrangement of parts as will fully appear by a perusal of the following specification and claims.

In the drawings similar characters of refer-

ence indicate corresponding parts in the several views:

Fig. 1 is a perspective outline of the front of a garage showing my improved door installed therein in a partly open or raised position.

Fig. 2 is an interior elevation of the door mounted in position and closed, with the surrounding frame or casing in section.

Fig. 3 is an enlarged cross section of the structure showing the door in its closed position.

Fig. 4 is an enlarged fragmentary cross section showing the members of the door in their raised or door opening positions.

Fig. 5 is a fragmentary perspective view of a pair of cooperating door channels.

Fig. 6 is a similar view broken out of the base member or sill of the door casing showing the catch structure.

Fig. 7 is an enlarged cross section of the door panels showing the same in their raised position.

Referring now more particularly to the characters of reference on the drawings, the casing of the door comprises a hollow base sill 1, upstanding hollow side members 2 at the ends of the base and relatively deep cap plates 3 extending between the sides at the top; said plates being spaced apart horizontally and lying flush with the front and back sides of said members 2. These plates have large openings extending transversely of the door area, the front or outer one of which is covered by a glass window arrangement 4. The parts above described are of sheet metal of the required quality and gage to give the necessary strength and are connected together in any suitable manner to form a rigid unit easily installed in place in connection with the standard studding and other frame-work 5 of the garage or other building in which the door is mounted.

The door itself comprises a number of separate panel-plates 6 which are also of sheet metal and which when extended relative to each other form a complete enclosure for the door opening, and then extend from the sill 1 to the lower edges of the cap plates 3, and of course between the sides 2. At their side

edges these panels project into slots 7 provided in the adjacent or inner sides of the uprights 2 from top to bottom, the edges of these slots adjacent the front face of the uprights being parallel thereto, while the other edges diverge from the bottom upwardly as clearly shown in Fig. 3.

Each panel is provided at the top with an inwardly projecting horizontal flange 8, the flanges of all the panels being all of different widths and the various widths being such that said different flanges will fit snugly between the sides of the slots at the levels occupied by said flanges when the panels are all extended. The various panels are so disposed that when extended their lower ends are in front of and overlap the upper ends of the successively lower panels, so that when said panels are raised they will be disposed inwardly of but close to each other in successive order from the uppermost panel down as shown in Fig. 4. At the same time the top flanges will then abut against and rest within each other. The panel flanges also project in front of the panels a short distance and are bent down in the form of lips to cooperate with and be engaged by the upturned grooved lower ends 9 of adjacent panels when the latter are extended as shown in Figs. 3 and 5, so that the panels have a substantially airtight fit with each other and in addition they are also hung in suspended relation from each other. Besides serving for the above named purposes it will be seen that the flanges 8 and the elements 9 also function as strengthening ribs for the panels at top and bottom, preventing any tendency for the panels to buckle between their ends.

The panels are held in close side by side relation with each other when raised, and the respective top flanges no longer fit snugly between the sides of the slot 7, by means of guide flanges 11 provided with the panels at the sides and parallel to and inwardly of the back faces of said panels a short distance. These flanges are slidable in transverse slots 12 cut in from the side edges of the flanges 8 just behind the respective panels. By reason of the above arrangement it will be seen that when the panels are raised they are maintained parallel and close to each other but when lowered they are disposed somewhat at a slant relative to a vertical plane in offset relation to each other but still being disposed in a substantially vertical plane as a whole.

The top flanges of the different panels when extended fit snugly between the sides of the slots 7 as previously stated. These flanges are prevented from jamming in the slots (whose sides taper toward each other) by reason of stops 13 projecting into the slots and on which the bottom of the topmost panel (from which all the others are sus-

pended as previously set forth) then rests as shown in Fig. 3.

The panels are automatically raised to a full door opening position by means of cables 14 at the sides which are secured only to the top flange of the lowermost panel and pass freely through the top flanges of the other panels. Above the level occupied by the top flange of the uppermost panel when raised said cables pass over pulleys 15 mounted in connection with the members 3 and connect with counterweights 16 which are movable vertically in the hollow members 2 behind their slotted walls. The combined weight of these counterweights need but be slightly greater than the weight of all the door panels together. This is because owing to the manner in which the panels are connected with each other, the weights only have to raise the lowermost panel first until its top flange engages the top flange of the adjacent panel above. The combined weight of these two panels alone is then taken by the counterweights and so on until all the panels are raised, the counterweights only sustaining the load of the entire door when the uppermost panel is being itself raised. These weights when initially starting to raise the door are very heavy compared to the weight of the relatively light parts which are then being moved, so that considerable momentum is imparted thereto. Therefore by the time the uppermost panel is engaged and move the momentum of the structure is sufficient to cause said uppermost panel as well as all the others to be then raised the necessary further distance to complete the full door opening movement.

The door when lowered is held in that position against the action of the counterweights by a rigid catch lug 17 depending from the bottom panel and adapted to project through a slot 18 in the upper face of the sill 1 and to then engage a transversely shiftable horizontal catch bar 19 which is pivoted at one end in the sill and is normally moved into engaging position with said lug by a spring 20. Various means may be employed to release the bar to permit the door to open. In the present instance I have shown such means as comprising a pull cable 21 extending from the free end of the bar to one of the side members 2, up the inside of said member to a certain height, and then outwardly in front and lengthwise of the garage some distance to a connection with a fixed post 22; said cable of course passing intermediate its ends over direction changing pulleys 23 wherever necessary. By means of this arrangement the catch may be released and the doors caused to open by the driver of a car without his leaving the driver's seat.

To enable the door to be lowered to a closed position handles 24 are mounted on

the forward face of the lowest panel adjacent the bottom.

From the foregoing description it will be readily seen that I have produced such a device as substantially fulfills the objects of the 5 invention as set forth herein.

While this specification sets forth in detail the present and preferred construction of the device, still in practice such deviations from 10 such detail may be resorted to as do not form a departure from the spirit of the invention 15 as defined by the appended claims.

Having thus described my invention what I claim as new and useful and desire to secure by Letters Patent is:

15 1. A door structure including a frame outlining the door opening, a plurality of vertically movable panels mounted in connection with the frame, said panels being extensible downwardly relative to each other 20 and when extended forming a closure for said opening, means for raising the panels to an opening-clearing position, each panel at its lower end when extended overlapping the upper end of the adjacent panel below, 25 and cooperating slide means between the panels to hold them against horizontal movement relative to each other.

2. A door structure including, with a 30 frame having side members, a plurality of vertically movable panels extending between the members, said panels being disposed in offset relation to each other and having their adjacent ends overlapping when the panels 35 are extended, horizontal flanges on the upper ends of the panels all extending in a common direction and being of proportionately decreasing widths from the topmost panel down, guide slots in the frame side members 40 into which the flanges project and having their sides converging from their upper ends downwardly to conform to the difference in width of the flanges, and raising means applied to the lowest panel.

3. A structure as in claim 2, in which the 45 panels when lowered are disposed so as to be parallel to the edges of the guide slots which engage the outer edges of the flanges whereby as each panel is raised it is confined in its movement between said edges of the 50 guide slots and the adjacent upper panel.

In testimony whereof I affix my signature.
WILLIAM ALDERSON.
